UNITED STATES PATENT OFFICE

EDWARD HARMON CAMPBELL, OF ECCLES, WEST VIRGINIA

SAND DRIER

Application filed June 17, 1931. Serial No. 545,120.

My invention relates to the type of sand driers which comprise a stove, a drum spaced above the stove, central means between the stove and the drum for conducting products of combustion from the former to the latter, and auxiliary conduits for products of combustion grouped about said central means and interposed between and connecting the stove and the drum; and it consists in the peculiar 10 and advantageous drier of said type, herein-after described and definitely claimed.

In the accompanying drawings, forming part of this specification:

Figure 1 is a side elevation of a drier embodying the features of my invention.

Figure 2 is a top plan view thereof.

Figure 3 is a detail sectional view showing one of the nipples with a tube engaged thereon.

Figure 4 is a horizontal section taken substantially on the line 4—4 of Figure 1.

Figure 5 is a horizontal section taken substantially on the line 5—5 of Figure 6.

Figure 6 is an elevation of the improved structure with some of the tubes removed, and

Figure 7 is an enlarged detail section taken substantially on the line 7—7 of Figure 1.

Referring to the drawings in detail it will be seen that the numeral 5 denotes a stove 30 with a hopper 6 mounted thereon in the usual well known manner. The upper portion of the stove has a dome 8 from the center of which rises a comparatively small bulbous like drum 9. A pipe 10 rises from the drum. 35 The lower portion of the drum 9 is provided with an annular series of openings 11. A plurality of nipples 12 are projected from the intermediate portion 7 of the stove in an annular series and incline upwardly and outwardly. Numerals 14 denote outwardly curved tubes, the upper ends of which are extended through the openings 11 and the lower ends of which are telescoped over the nipples 12.

40 A fire box door 15 is provided in the lower portion of the stove below the annular series of nipples 12. The sand is placed in the hopper in the usual well known manner and the heat is more thoroughly distributed 45 through the sand because of the construction 50

of the stove in combination with the tubes 14 and the drum 9.

This will be better understood when it is pointed out that by virtue of the dome-shape of the upper end of the stove and the comparatively small size of the drum 9 the products of combustion will be retarded en route between the stove and the drum 9 with the result that a considerable portion of the products of combustion will be caused to pass 60 through the tubes 14, and in consequence heat will be radiated not only through the sand immediately adjacent to the stove but also through the sand surrounding and outwardly beyond the tubes 14. It will also be noted 65 that the upper and discharge end of the drum 9 is contracted which contributes to the retardation of the heated products of combustion en route to the uptake 10, and that by virtue of the outwardly curved form of the tubes 14 the length of the portions of the tubes 14 in the sand is increased and the radiating surface of the tubes 14 is further increased. 70 It will further be noted that because of the specific construction disclosed the tubes 14 75 may be expeditiously and easily arranged in working position relative to the stove and the drum 9.

It is thought that the construction, utility and advantages of this invention will now be 80 quite apparent to those skilled in this art without a more detailed description thereof.

The present embodiment of the invention has been described in considerable detail 85 merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages. 90

Having thus described my invention, what I claim as new is:

1. A sand drier comprising a hopper, a stove arranged in the central portion of the hopper and having a dome-shaped upper end 100

portion, a drum of comparatively small diameter communicating directly with the stove at the upper contracted end thereof and tapered upwardly to provide it with a reduced upper end, an uptake leading from said upper end of the drum, and outwardly curved tubes grouped about the stove and the drum and having their ends connected with the interiors of the stove and drum, said outwardly curved tubes being spaced apart.

2. A sand drier comprising a hopper, a stove arranged in the central portion of the hopper and having a dome-shaped upper end and also having a series of nipples extending outwardly from its intermediate portion and grouped about said portion and communicating with the interior of the stove, a drum of comparatively small diameter connected with the upper central portion of the stove and having an upwardly tapered upper portion and also having in its lower portion a circular series of apertures, and a plurality of outwardly curved tubes grouped about the stove and the drum in spaced relation and disposed over the said nipples and having their upper ends disposed in the said apertures of the drum.

In testimony whereof I affix my signature.

EDWARD HARMON CAMPBELL.
